EDWARD SABINE RENWICK, OF NEW YORK, N. Y.

Letters Patent No. 87,112, dated February 23, 1869.

IMPROVEMENT IN GRATES.

The Schedule referred to in these Letters Patent and making part of the same.

To all whom it may concern:

Be it known that I, EDWARD SABINE RENWICK, of the city, county, and State of New York, have invented certain new and useful Improvements in Grates for Furnaces, Stoves, and other Apparatus for Burning Fuel; and that the following is a full, clear, and exact description and specification of my said invention.

The objects of the invention which constitutes the subject-matter of this patent, are to enable a round grate to be cleansed of ashes and of clinker with greater facility than heretofore. To this end,

The first part of my invention consists of the combination of one or more stationary circular grate-bars with one or more other grate-bars, movable in a circular direction, the whole constructed and operating in such manner that the movable bar or bars can be turned or vibrated upon the vertical axis of the grate, or thereabout, while the other bar or bars do not move with them; hence, when the movable bars are turned or vibrated horizontally, the coals lying upon them are also moved, while the stationary bars support a part of the weight of the fire, and also, by retarding the movement of those parts of the coals which rest upon them, cause the coals to turn, or oscillate under the action of the movable bar or bars.

My invention consists, further, of the combination of the fixed circular bar or bars, and the movable circular bar or bars, (turning on a vertical axis,) with a horizontal rock-shaft, or journals, so that the grate may be tipped to discharge the contents of the fire-box.

My invention consists, further, of the combination of a grate arranged to tip on a horizontal axis, crossing it diametrically, or thereabout, with a fire-box, or pot, that is curved at one side concentrically, or thereabout, with the tipping-axis, so that when the grate is partly tipped, to permit cinders to be drawn out at the depressed side of the grate, cinders are not permitted to jam in at the rising side of the grate, and consequently the restoration of the grate to a horizontal position is not obstructed materially by such cinders or clinker.

In order that my invention may be fully understood, I have represented, in the accompanying drawings, one of the modes in which all parts of the invention may be embodied in a practical form.

Figure 1 represents a horizontal section of the fire-pot of a hot-air furnace, with the invention applied thereto;

Figure 2 represents a vertical transverse section of it, crosswise to the tipping-axis of the grate; and

Figure 3 represents a similar section of it, through the tipping-axis of the grate.

The drawings represent only such parts of a furnace as are necessary to enable the invention to be understood, the residue being constructed in any suitable manner.

The fire-pot, or box A, is of circular form, and the grate is composed of two parts or sets of grate-bars, both circular, and concentric with the axis of the fire-pot.

One set of the grate-bars *a a* is prevented from turning in a horizontal plane, by being secured to a rock-shaft, B. The other set, *c c c*, is constructed to turn upon a pivot, *e*, which is vertical, or perpendicular to the plane of the grate, and is sustained by the rock-shaft B, so that this set may be turned or vibrated in a horizontal plane.

This movable set of bars is provided with a socket, to which a lever, C, may be applied, and by which the movable set may be turned in a circular direction.

The rock-shaft B terminates at its ends in journals *d d*, which are sustained in suitable bearings sustained by the walls of the ash-pit of the furnace; hence, the whole grate may be tipped upon the axis of said journals as a tipping-axis, the front side of the grate being depressed, and the rear side rising, for the purpose of discharging the contents of the fire-pot.

In order to prevent the grate from being tipped in the wrong direction, a guard, *f*, is secured to the rear wall of the ash-pit, beneath the rear side of the grate, and in practice, I prefer to arrange the tipping-axis a little nearer the front of the grate than the rear side thereof, so that the preponderance of weight at the rear of the tipping-axis will prevent the accidental tipping of the grate.

In stoves and furnaces constructed heretofore with tipping-grates, (so far as I am aware,) the fire-pot is either cylindrical above the grate, or gradually widens; hence, when the grate is tipped, the space *s*, between the rising side of the grate and the adjacent side of the fire-pot, grows wider as the grate rises at that side, and, as a natural consequence, coals or pieces of clinker that would not pass through the space *s* when the grate is horizontal, can get into that space when the grate is partly turned up. In practice, such pieces do get into the space when the grate is turned up, and they obstruct or prevent the restoration of the grate to a horizontal position.

To obviate this difficulty, I contract the side of the fire-pot, at *r*, adjacent to the rising side of the grate, making it, by preference, concentric, or thereabout, with the tipping-axis of the grate; hence, when the grate rises at that side, by the act of tipping, the space *s* does not increase in width, and consequently no pieces of coals or other material can pass into that space, which will not pass through it when the grate is restored to a horizontal position.

This construction facilitates the removal of clinkers without discharging all the contents of the fire-pot, because the grate may be partly tipped so as to open the fire-pot at the front, to permit the clinkers to be drawn out, and afterward, (as jamming at the rear side of the grate is prevented,) the grate may be readily restored to its horizontal position.

In practice, I prefer to cast all the parts of the movable part of the grate in one piece, and to secure the members of the stationary part to each other by lugs or by screws. (See Figure 4.)

In hot-air furnaces set in brick casings, where the fire-pot is at a considerable distance from the face of the casing, I connect the movable part of the grate with a rock-shaft, by means of a link, and dispense with the direct application of the lever *f* to the movable part.

In such a furnace, the rock-shaft may extend through the ash-pit, perpendicular to the face of the casing, and may be fitted at its front end with a shaking-lever; or the rock-shaft may be placed in front of the casing, with its axis parallel thereto, and the link may extend through a hole in the front of the ash-pit, from an arm of the rock-shaft to a lug projecting from the movable part of the grate, in the vicinity of the rock-shaft *B*.

The rock-shaft, at the front of the casing, is then provided with a shaking-lever.

The efficiency of the apparatus may be increased by forming the upper surface of the movable bars with projections.

I am aware that circular grates have been made to tip upon a horizontal axis, long prior to my invention, and that the entire grate has been constructed to turn or vibrate altogether upon a vertical axis, as well as to tip upon a horizontal axis. I do not, therefore, claim such constructions; but

What I claim as my invention, and desire to secure by Letters Patent, is—

The construction of the circular grate of two parts, one of which is constructed to move in a circular direction relatively to the other, the two parts being so combined, that the movable part can be turned upon an axis which is perpendicular to the plane of the grate, substantially as before set forth.

Also, the combination of the fixed and movable parts of the circular grate, (the latter constructed to turn, relatively to the former, upon an axis that is perpendicular to the plane of the grate,) with horizontal journals, on which the grate may be tipped, substantially as before set forth.

Also, the combination of the grate, constructed to tip upon a horizontal axis crossing it diametrically, with a fire-pot, curved at one side of the grate, concentrically with the tipping-axis of the grate, substantially as before set forth.

In testimony whereof, I have hereto set my hand, this 5th day of December, A. D. 1868.

E. S. RENWICK.
